UNITED STATES PATENT OFFICE.

FRANK OLIVER PORTER, OF WOLLASTON, MASSACHUSETTS, ASSIGNOR TO LOUIS S. ROTHENBERG, OF BOSTON, MASSACHUSETTS.

PENCIL-SHARPENER.

No. 894,781.

Specification of Letters Patent.

Patented July 28, 1908.

Application filed November 5, 1907. Serial No. 400,766.

To all whom it may concern:

Be it known that I, FRANK OLIVER PORTER, a citizen of the United States of America, and a resident of Wollaston, in the county of 5 Norfolk and State of Massachusetts, have invented certain new and useful Improvements in Pencil-Sharpener, of which the following is a specification.

This invention relates to pencil sharpeners 10 and has for its object the production of a machine in which a pencil of any size may be held rigidly while a revoluble cutter operates upon the same to sharpen it, the chips caused by said sharpening being delivered to a receptacle which is arranged to receive them, whether the receptacle is secured to a wall or 15 to a table.

The invention consists in certain novel features of construction and arrangement of 20 parts which will be readily understood by reference to the description of the drawings and to the claims hereinafter given.

Of the drawings: Figure 1 represents an elevation of a pencil sharpener embodying 25 the features of this invention. Fig. 2 represents an end view of the same. Fig. 3 represents a section of the same, the cutting plane being on line 3—3 on Fig. 1. Fig. 4 represents a transverse section of the same, the 30 cutting plane being on line 4—4 on Fig. 2. Fig. 5 represents an elevation of the upper part of the end opposite that shown in Fig. 2. Fig. 6 represents an elevation of the jaw-carrying support. Fig. 7 represents a section 35 of the same, the cutting plane being on line 7—7. Fig. 8 represents a section through the main portion of the chip receptacle. Figs. 9 and 10 represent perspective views of the detachable sides therefor, and Fig. 11 40 represents a detail showing the devices for locking the detachable sides to said main portion.

Similar characters designate like parts throughout the several figures of the drawings. 45 In the drawings, 12 represents a U-shaped member bent into the position shown in Figs. 1 and 4 from a metal plate, one side 12^a thereof being provided at its outer end with a bearing 13 while the other side 12^b thereof 50 has fixed in its outer end a bearing 14 which is provided with a plurality of radial slots 15 in each of which is adapted to be mounted a radial gripping jaw 16. The periphery of the annular bearing 14 is provided with a 55 groove 17 in which projects the inner edge

of a plate 18 having extending therethrough a plurality of eccentric cam slots 19 into which extend the outer projecting ends 20 of the radial jaws 16. The plate 18 is provided with a handle 21 by which said plate may be moved about the bearing 14 in the groove 17, thereby causing the radial jaws 16 to be moved toward and from the axis of said bearing 14.

A spring 22 is secured at 23 to the side 60 plate 12^b of the U-shaped member 12 while the opposite end of said spring is secured at 24 to the plate 18, the tension of said spring being such as to normally retain the disk plate 18 in the position shown in Fig. 2 with 65 the jaws 16 in their innermost position. Supported in the bearings 13 and 14 is a revoluble member 25 provided with a conical receptacle 26 into which slightly projects the cutting edge of a tangential cutter blade 27 70 secured to said revoluble member by a screw 28. The receptacle 26 is in axial line with the center of the bearings 13 and 14 and it is adapted to receive therein the end of a pencil 75 which it is desired to sharpen. Riveted to 80 the outer end of the revoluble member is a handle 29 by which the member 25 may be revolved to cause the blade 27 to act upon the end of the pencil inserted within the receptacle 26 and shave therefrom a certain 85 amount of wood and lead to cause a pointing thereof. The superfluous material thus shaved from the pencil passes from said receptacle 25 through the radial opening 30 into the chip receptacle 31. A passage 32 90 extends from the inner end of the chamber 26 to the opposite end of the revoluble member 25 to permit the fine lead at the point of the pencil to pass freely therethrough.

The bottom portion 12^c of the U-shaped member 12 is provided at either edge thereof intermediate the sides 12^a and 12^b with slots 33 with which the projection 34 on the ends of the side plates 35 and 36 are adapted to co-act, to position them relative to the sides 12^a and 12^b. When the projecting members 34 have been inserted in the slots 33 the T-shaped projections 37 from the edges of said side plates 35 or 36 are adapted to engage 100 with notches 38 in the edges of the side members 12^a and 12^b to securely lock the side plates 35 and 36 in position to form the chip receptacle 31. Each of the notches 38 is 105 provided with a slight shoulder 39 which retains the projecting members in position un- 110

til force is applied thereto to spring the projecting member over said shoulder when it is desired to dismantle the receptacle. The side plate 35 is provided with an extension 40 which partially surrounds the revoluble cutting member 25, this extension being chiefly used when the receptacle 31 is attached to a side wall with the plate 35 utilized as the bottom of the receptacle. Openings 41 through 10 the bottom plate 12^c of the U-shaped member 12 are provided by which with suitable screws the device may be secured either to a table or a side wall. This makes a very cheap construction of a pencil sharpener, the 15 receptacle and all of the parts thereof being struck out of sheet metal which are readily locked together without rivets, screws, or other instrumentalities.

The gripping device is so situated as to 20 clip the pencil in axial line with the revoluble cutting member and the spring 22 operates to hold the gripping jaws always in contact with the pencil during the operation of cutting.

25 It is believed that the operation of the invention and the many advantages of a device of this construction will be thoroughly apparent from the foregoing without any further description.

30 Having thus described my invention, I claim:

1. In a pencil sharpener, the combination of a revoluble cutting member; and a recep-

tacle beneath said cutting member for the reception of the chips, consisting of a box 35 having two sides each provided with notches in the edges and sides having projecting members adapted to engage said notches.

2. In a pencil sharpener, the combination of a revoluble cutting member; and a chip 40 receptacle beneath said revoluble cutting member, consisting of a U-shaped member having slots in the bottom portion and notches in the edges of the sides and detachable sides having projecting members at one 45 end adapted to engage said slots and other members projecting from the edges thereof adapted to engage said notches.

3. In a pencil sharpener, the combination of a revoluble cutting member; and a chip 50 receptacle beneath said revoluble cutting member, consisting of a U-shaped member having slots in the bottom portion and notches in the edges of the sides and detachable sides having 55 projecting members at one end adapted to engage said slots and other members projecting from the edges thereof adapted to engage said notches, one of said detachable sides being extended to partially surround said revoluble member.

Signed by me at Boston, Mass., this 22d 60 day of October, 1907.

FRANK OLIVER PORTER.
